UNITED STATES PATENT OFFICE.

JEROME BOLICK, OF CONOVER, NORTH CAROLINA.

WHEEL.

Application filed May 13, 1922. Serial No. 560,645.

This invention relates to wheel constructions, and aims to provide a novel construction wherein a wheel may be removed from its axle eliminating any possibility of the usual 5 brake drum which is secured to the wheel hub becoming loose from its supporting plate.

Another object of the invention is to provide a wheel construction which may be 10 readily and easily applied to the usual axle now in use, eliminating the necessity of making alterations in the present construction to accomplish the positioning of the wheel.

Another object of the invention is to provide 15 a structure wherein the usual hub of a wheel may be employed in converting a wooden wheel into a metallic wheel.

With the foregoing and other objects in view which will appear as the description 20 proceeds, the invention resides in the combination and arrangement of parts and in the details of construction hereinafter described and claimed, it being understood that changes in the precise embodiment of the invention 25 herein disclosed, may be made within the scope of what is claimed, without departing from the spirit of the invention.

Referring to the drawings:—

Figure 1 is a side elevational view of a 30 wheel constructed in accordance with the invention.

Figure 2 is a sectional view taken on line 2—2 of Figure 1.

Figure 3 is an elevational view disclosing 35 the inner portion of the metallic hub section forming a part of the wheel.

Figure 4 is an elevational view disclosing a modified form of a metallic hub used with 40 metal spokes.

Figure 5 is a sectional view through a modified form of metallic hub.

Referring to the drawings in detail, the reference character 5 designates the usual 45 tubular bearing member of a hub, on which is positioned the metallic one piece hub section 6, which is circular in formation and provided with a plurality of recessed portions 7, the side walls thereof being inclined as at 8, for purposes to be hereinafter 50 more fully described.

Arranged in the metallic hub section 6 and disposed between the side walls of predetermined recessed portions are the openings 9 which accommodate the securing bolts 10 55 that are employed for securing the metallic hub section to the retaining disk of the hub.

This securing disk is indicated at 11 and is shown as engaging the inner surface of the metallic hub section 6. A circular rib 12 is formed on the disk 11 and provides a shoulder to be engaged by the wall of the opening formed centrally of the brake drum 13, so that the brake drum will be held against lateral movement with respect thereto. 65

The bolts 10 which form an important feature of the invention are shown as formed with enlargements 14 that are formed with flat shoulders to contact with the inner surface of the securing plate 11 to force the plate 11 and drum 13 into close engagement with each other, when the nuts 15 have been properly positioned. In connection with the foregoing it might be stated that due to this construction, movement of the bolts laterally, is restricted. The side faces of the bolts 10 are curved to conform to the curvatures of the side walls 8, as clearly shown by Figure 2 of the drawings. Due to this construction, it will be obvious that the bolts 70 are locked against movement and prevented from rotating to loosen the nuts that are secured to the ends thereof. 75

Openings 16 are formed in the hub sections 6, which openings accommodate the spokes 80 17 which are metallic and provided with tapered end portions. These spokes are formed with relatively flat side faces permitting the spokes to flex when the wheel passes over obstructions in the road surface. 85 The invention is shown as applied to a metallic wheel structure embodying the usual clincher rim, the rim being indicated at 18 and secured to the socket members 19, that receive the spokes 17, in any suitable and well 90 95 manner.

In the form of the invention as illustrated by sheet 2 of the drawings, the metallic hub section is indicated at 20, which hub section is formed with a plurality of openings 21 to accommodate the spokes of the wheel. 100

The main hub section is indicated at 22 and is formed with an inner flange member 23 and a tubular section 24, the tubular section 24 being designed to accommodate the disk 25 which also closely engages the opposite side of the hub section 20. The hub section 22 accommodates the brake drum 26, the brake drum being secured to the hub 105 section by means of the bolts 27, which bolts are also formed with enlargements 28 con- 110

tacting with one surface of the flange member 23, the nuts 29 operating on the threaded portions 30 of the bolts, cooperating with the enlargements to clamp the flange member 23 and hub section together.

Nuts 31 are secured to the opposite ends of the bolts 27 to prevent movement of the disk 25.

Having thus described the invention, what is claimed as new is:—

A wheel construction embodying a one-piece hub section, said hub section having radiating openings to receive spokes, said hub section having transversely disposed

openings arranged between the first mentioned openings, a disk mounted at one side of the hub section, bolts extending through the transversely disposed openings and having enlargements defining shoulders, said shoulders adapted to engage the disk, nuts on the ends of the bolts and adapted to cooperate with the shoulders to clamp the disk in position, and an inner bearing member removably supported within the hub section.

In testimony that I claim the foregoing as my own, I have hereto affixed my signature.

JEROME BOLICK.
